DESIGN FOR A LAMP BASE

Goswin Marcin and Morris R. Silverman,
Highland Mills, N. Y.

Application November 29, 1940, Serial No. 96,950

Term of patent 14 years

To all whom it may concern:

Be it known that we, Goswin Marcin and Morris R. Silverman, citizens of the United States and residents of Highland Mills, in the county of Orange and State of New York, have invented a new, original, and ornamental Design for a Lamp Base, of which the following is a specification, reference being had to the accompanying drawing, forming a part thereof, in which

Fig. 1 is a side elevational view of a lamp base showing our new design; Fig. 2 is a top plan view of the same; and Fig. 3 is a rear view of the same.

We claim:

The ornamental design for a lamp base, substantially as shown.

GOSWIN MARCIN.
MORRIS R. SILVERMAN.
